NIBBLING ATTACHMENT FOR DRILL PRESSES

Clair W. Heydenburg, Los Angeles, Calif.

Application September 3, 1938, Serial No. 228,412

1 Claim. (Cl. 164—47)

This invention relates generally to power tools, and more particularly to drill presses.

An object of the invention is to provide a nibbling device particularly adapted, although not necessarily for use in conjunction with a power drill press, by utilizing the latter as a support and as a driving means, all in such manner that the device will not require any means to fasten it in place and will not subject the drill press spindle to any destructive forces or premature wear, yet will enable the device to rapidly and accurately nibble away the edge of sheet metal or other material as fed to the nibbling punch of the device by an operator, whereby to eliminate a separate and costly nibbling machine requiring large floor area and, therefore, not available for relatively small machine shops.

Another object of the invention is to provide a nibbling device of the above described character having means by which it can be readily adjusted to compensate for wearing away of the nibbling punch and for internal nibbling operations, as well as enabling the nibbling punch to be rotatively adjusted in order that work can be fed to the punch from various directions.

A further object of the invention is to provide a nibbling device which is relatively inexpensive, extremely compact so as to render it conveniently portable, and which can be applied to and removed from a drill press with the utmost ease and dispatch.

With these and other objects in view, the invention resides in the combinations, arrangements and functional relationships of elements as set forth in the following specification, and particularly pointed out in the appended claim.

In the accompanying drawings,

Figure 1 is a view in side elevation, and showing the nibbling device embodying this invention applied to a drill press;

Figure 2 is a horizontal sectional view taken on the line 2—2 of Figure 1;

Figure 3 is an enlarged vertical longitudinal sectional view of the nibbling device, taken on the line 3—3 of Figure 2, and showing the nibbling punch in its upper extreme position;

Figure 4 is a sectional view similar to Figure 3 and showing the nibbling punch in its lower extreme position.

Referring specifically to the drawings, the invention comprises a support 10 including a rectangular base portion 11 having a work plate 12 and feet 13 at its corners on which the support can be rested upon the table T of a drill press P. From the base portion 11 projects an overhang-

ing arm 14, the free end of which is provided with an opening 15 therethrough, slidably receiving a mounting sleeve 16 externally threaded at 17 and 17a to receive nuts 18 and 19 adapted to co-act with opposite sides of the arm in clamping the sleeve thereto in various axially and rotatively adjusted positions for a purpose to be later described.

Mounted in the cylindrical bore 20 of the mounting sleeve 16 is a punch holder 21 confined to reciprocating motion in the sleeve by means of a pin 22 threaded into the holder and working in a longitudinal slot 23 in the sleeve. The upper end of the holder is of a diameter to provide a working fit in the bore 20, whereas the remainder of the holder is of reduced diameter to provide an annular space between the holder and sleeve for a coil spring 24 which abuts the lower end wall 25 of the sleeve and the enlarged upper end of the holder for co-action therewith in urging the holder upwardly.

The lower end of the holder is guided by and projects through an opening in the end wall 25 and is provided with a socket 26 receiving a nibbling punch 27 secured in place by a set screw 28. During reciprocating motion of the holder 21, the punch 27 co-acts with a die 29 secured by a set screw 30 in a socket 31 provided in the base portion 11 in co-axial relationship to the axis of the holder and mounting sleeve.

The upper end face of the holder 21 is formed to provide a cam 32 with which is adapted to coact a complementary cam 33 formed on the lower end face of a stub shaft 34 rotatably mounted in a plain bearing 35 supported by a cap 36 threaded at 37 into the upper end of the mounting sleeve 16. A ball thrust bearing 38 is interposed between the shaft and cap, and nuts 39 and 40 are threaded on the shaft at 41 for co-action with the bearing 38 in confining the shaft against axial displacement.

The upper end of the shaft 34 is reduced in diameter to form a shank 42 adapted to be received and clamped in the chuck C of the drill press P when the support 10 is resting on the table T of the press as is shown in Figure 1, whereby to provide a detachable driving connection by which the shaft 34 will be driven by the spindle S journaled in the head H of the drill press.

The support 10 is provided with a boss 43 in which is screwed a rod 44 having a sleeve 45 of elastic rubber and forming an arm of sufficient length to engage the column K of the drill press for co-action therewith in preventing rotation of

the support 10 on the table T during the operation of the invention, which is as follows:

With the support 10 resting on the table T and with the shank 42 clamped in the chuck C, the 5 arm 44 is engaged with the column K, following which the drill press is set in operation to cause its spindle S and hence the shaft 34 to be rotated.

It will be noted that the spring 24 tends to 10 constantly maintain the cam 32 in contact with the cam 33 by urging the holder 21 axially upward to the extreme position shown in Figure 3, wherein the nibbling edge or shoulder 27a of the punch 27 clears the platen 12 sufficiently for the insertion of the metal to be worked upon between 15 the punch and platen.

As rotation of the shaft 34 is effected, the cams 20 32 and 33 co-act to force the holder 21 axially downward against the action of the spring 24, to the other extreme position shown in Figure 4, 25 wherein the nibbling edge 27a of the punch 27 enters the die 29. It will thus be clear that by manually feeding a sheet of metal on the platen 12, and properly manipulating the edge of the metal with respect to the punch 27, the latter will nibble away the edge so that the edge can be given any contour desired.

By loosening the nuts 18 and 19, the mounting 30 sleeve 16 can be raised or lowered to vary the working position of the punch 27 vertically with respect to the platen 12 so as to compensate for 35 wearing away of the nibbling edge 27a as well as to dispose such edge at the position most effective in nibbling metal of a particular thickness. By this arrangement, the mounting sleeve can also be raised sufficiently to clear the punch 27 from the platen in order to permit a sheet of metal to be inserted beneath the punch for internal nibbling. Likewise the mounting sleeve can also be 40 rotatively adjusted to vary the circumferential position of the nibbling edge, and thus permit the

work to be fed to and acted upon by the punch from various directions, whereby to accommodate sheets of various proportions and contours.

It will be noted that as the nibbling device merely rests upon the table T and is entirely free of any direct attachment thereto by a rigid or extraneous fastening means, no destructive forces incident to the driving of the shaft 34 by the spindle S will be set up in the latter, and that the spindle will be subjected only to the usual 10 torque and end thrust as are imposed thereon in drilling operations. The functioning of the arm 44 does not affect this condition, as the arm merely prevents rotation of the device on the table T, under the rotative tendency of the shaft 15 34.

What is claimed is:

A nibbling device comprising a support having a die; a mounting sleeve axially and rotatively adjustable in the support and co-axially related to said die; nuts on the sleeve co-actable with the support to secure the sleeve in a selected position of adjustment; a punch holder mounted in the bore of the sleeve; a nibbling punch carried by the holder and co-actable with the die; means for confining said holder to reciprocating motion axially in the sleeve; a cam on an end face of said holder; a shaft journaled in said holder and having a cam on an end face thereof co-actable with the cam of the holder to move the latter to one extreme position in response to rotation of the shaft; a spring in the sleeve co-acting with the holder to urge the latter to its other extreme position; a shank on said shaft adapted to be clamped in the chuck of a drill press when the support is disposed on the table of the press; and an arm on the support adapted to engage the column of the drill press to prevent rotation of the support. 30 35
